UNITED STATES PATENT OFFICE.

SAMUEL T. WELLMAN, OF CLEVELAND, OHIO, FRED H. DANIELS, OF WORCESTER, MASSACHUSETTS, AND CHARLES H. WELLMAN, OF CLEVELAND, OHIO.

ROLLING-MILL.

SPECIFICATION forming part of Letters Patent No. 645,306, dated March 13, 1900.

Application filed August 10, 1899. Serial No. 726,818. (No model.)

To all whom it may concern:

Be it known that we, SAMUEL T. WELLMAN, of Cleveland, in the county of Cuyahoga and State of Ohio, FRED H. DANIELS, of Worcester, in the county of Worcester and State of Massachusetts, and CHARLES H. WELLMAN, of Cleveland, in the county of Cuyahoga and State of Ohio, have invented a certain new and useful Improvement in Rolling-Mills, of which the following is a specification.

The rolling-mill in which our invention is comprised is one which may be termed a "continuous" ingot-blooming mill, and it has been designed more particularly with a view to rolling cast-steel ingots as they come, for example, from the continuous heating-furnace which is the subject of our application filed June 30, 1899, Serial No. 722,455, although it may be used in other connections.

Our rolling-mill consists, generally speaking, of a number of pairs of power-driven rolls placed tandem, or one after the other, combined with intermediate power-driven roller-tables which can be stopped and started at pleasure, and even reversed, if that movement also be desired. The rolls are of sufficient length for two grooves or passes. The ingot in its passage through the first series of grooves is partially reduced, and the partly-finished product is then carried back by suitable means and passed through the second series of grooves, by which it is fully reduced. The pairs of rolls are so spaced apart that during the first pass the product comes out from between one pair of rolls before entering the next pair. It can thus be removed in case of accident, the roller-table on which it rests being of course stopped for this purpose. On the other hand, during the second pass or travel of the product through the second series of grooves the original ingot has become elongated to such an extent that the rolling process is continuous, the product in no case coming out from one pair of rolls before it enters the next pair. In this way we avoid the expense of duplicating the pairs of rolls in the mill, which would involve a double

outlay, and otherwise simplify the plant. It is desirable to present new faces of the product during its passage through the mill to 50 the reducing action of the rolls. Inasmuch as the product during the first pass quits one pair of rolls before it enters the next, it can be turned by any suitable manipulator at this time while it is resting on the roller-table; but at the second pass inasmuch as the product engages one pair of rolls before it quits the other other means for turning the product must be provided, for which purpose we employ twist-guides. 60

The nature of our improvement can, however, best be explained and understood by reference to the accompanying drawings, in which—

Figure 1 is a plan view, Fig. 2 is a side 65 elevation, and Fig. 3 is an end elevation, of a roller-mill embodying our invention. These three figures are largely diagrammatic and are intended to illustrate the general scheme or plan of the mill. The remaining figures— 70 viz., Figs. 4, 5, and 6—are upon a larger scale and are intended to illustrate more clearly the structural details of the mill. Fig. 4 is a plan representing one of the pairs of rolls, together with the roller table or tables 75 and other appurtenances adjacent to said pairs of rolls, the end housings or supporting-frames of the reducing-rolls being in horizontal section. Fig. 5 is a side elevation of said parts. Fig. 6 is an end elevation of the 80 same, showing also details of the connections between the reducing-rolls and the power by which they are driven, the details last referred to being omitted from Figs. 4 and 5.

In the mill shown in the drawings, referring more particularly now to Figs. 1 to 3, there are six pairs of reducing-rolls R' to R⁶, inclusive, placed in line one after the other, each separated from the one in advance by a suitable interval, as hereinbefore explained, 90 and combined with intervening power-driven rollers, forming roller tables or sections lettered T to T⁶, inclusive. Each roll is made sufficiently long to receive two grooves, and

in each there are formed two parallel grooves $r' r^2$, Figs. 4 and 6, the former for the first pass and the latter for the second pass of the product through the mill. The rolls of each 5 pair are housed in a suitable frame H, and all of them are driven from one engine a, whose driving-shaft c is engaged by bevel-gearing b' to b^6 , inclusive, Fig. 1, to cross-shafts, to which the pairs of rolls are respectively coupled by pinions and shafting d' to d^6 , inclusive, Figs. 1 and 6. The bevel-gears b' to b^6 are of course so proportioned, as indicated in Fig. 1, as to impart to the successive pairs of rolls the progressively-increased 10 speed required. The rollers forming the roller table or tables are driven from one or more electric motors M or other suitable motors. In this instance there are shown three motors M, Fig. 1, and the series of rollers may be divided up into sections, each driven by its own motor. The rollers are suitably housed in the longitudinal framing of the mill and are driven by beveled gearing m from a shaft m' , extending lengthwise of the mill, Figs. 4, 5, 15 and 6, which shaft is driven by gearing m^2 , Fig. 4, from the motor M. At the point where this shaft m' meets the roll frames or housings H it is interrupted, and motion is transmitted from one shaft-section to the next by 20 means of the pinions m^3 and shaft m^4 , as seen in Fig. 5.

At the discharge end of the mill is a shear S, Figs. 1 and 2, actuated from a steam-cylinder S' or other suitable motor, and we also 25 provide a light traveling overhead crane E, which is intended to take the partially-reduced ingot after the first pass has been completed and to quickly transfer it back to the front end of the mill and to place it upon the 30 roller-table at that point in position for the second pass. In lieu of this transferring device other means can be employed—as, for example, a power-driven auxiliary roller-table arranged alongside of the mill. In this 35 case the partially-reduced product after being delivered from the last pair of rolls will be shifted sidewise upon the auxiliary roller-table, carried back by said table to the front end of the mill, shifted sidewise again in front 40 of the proper groove in the reducing-rolls, and again passed through the mill. In its first 45 passage through the mill any suitable means of turning the ingot—as, for example, a manipulator (typified at A, Fig. 4)—may be employed, because the ingot at this time is not 50 of a length to engage two pairs of rolls at once; but in passing a second time through the mill the partially-reduced product is of such length that it enters the pair of rolls in 55 front before it quits the pair in rear. Therefore we provide in connection with the second 60 set of grooves in the reducing-rolls twist-guides of any suitable known kind, (typified at G, Fig. 4,) by which the first end of the 65 product is given a sufficient spiral movement

or twist that it will have been turned ninety degrees by the time it enters the second pair of rolls.

The mode of operation is as follows: The hot ingot, which weighs about three thousand pounds and is about sixteen inches by sixteen inches in cross-section, is taken from the heating-furnace by a traveling crane or other suitable means and laid upon the roller-table in front of the primary set of grooves r' of the 70 first pair of reducing-rolls R'. It is carried forward to and passes between this pair of rolls out upon the rolling-table T' beyond, being of such length that it quits the first pair of rolls R' before it reaches the second pair 75 R². It is then turned so as to present fresh faces to the second pair of rolls R², between which it then passes out onto the roller-table T² beyond and so on until it has passed between and beyond the last or finishing pair of 80 rolls R⁶, by which time it will have a cross-section (square in shape) of about eight inches by eight inches and will be correspondingly elongated. The first end of the partially-reduced ingot is next sheared off by the 85 shear S, and the product is then seized by the traveling crane E and quickly transferred back to the front end of the mill onto the roller-table T in front of the second set r^2 of 90 grooves in the reducing-rolls. It thence 95 passes again through the mill, this time through the grooves r^2 , with which the reducing-rolls are respectively provided. By the time it has passed this second time beyond the finishing-rolls R⁶ it will have been reduced 100 to the shape of a rod or bar about four inches by four inches in cross-section. By its first 105 passage through the mill the original ingot was elongated to such an extent that during its second passage therethrough, which reduces it from eight inches by eight inches to four inches by four inches in cross-section, the rolling process is a continuous one, the product reaching to and beyond the pair of rolls in front before leaving the pair of rolls 110 behind. In order therefore to present new 115 faces of the product to the reducing action of the rolls, we employ twist-guides G, as hereinbefore described, during its passage through which the product is given a turn of ninety 120 degrees, or thereabout. The product passing out from the grooves r^2 of the final or finishing pair of rolls R⁶ is then cut up into the lengths required for further treatment (usually four feet long) by means of either fixed 125 shears or rotary shears, as may be required. If fixed shears are used, the entire product—that is, the entire length of the reduced ingot—comes out from the last pair of rolls before the shearing operation. If rotary shears 130 be used, the product is cut up just as fast as it comes out from between the last pair of rolls.

Having now described our improvement and the best way at present known to us of 130

carrying the same into effect, what we claim herein as new, and desire to secure by Letters Patent, is as follows:

The combination of the series of pairs of 5 reducing-rolls provided each with reducing grooves or passes r' , r'' , the roller-tables, twisting-guides for turning the product during its second passage through the rolls, and means for transferring the partly-reduced product 10 back to the front of the mill, these elements being constructed and arranged together for joint operation, substantially as and for the purposes hereinbefore set forth.

In testimony whereof we have hereunto signed our names in the presence of subscr- 15 ing witnesses.
